Primary Examiner — Jonathan J Han(74) Attorney, Agent, or Firm — Michael Best & Friedrich LLP(57) CLAIM

I claim the ornamental design for a shoe, as shown and described.

DESCRIPTION

FIG. 1 is a perspective view of a shoe in accordance with a first embodiment of the design;

FIG. 2 is a right side view of the shoe of FIG. 1;

FIG. 3 is a left side view of the shoe of FIG. 1;

FIG. 4 is a front view of the shoe of FIG. 1;

FIG. 5 is a rear view of the shoe of FIG. 1;

FIG. 6 is a top view of the shoe of FIG. 1; and

FIG. 7 is a bottom view of the shoe of FIG. 1.

FIG. 8 is a perspective view of a shoe in accordance with a second embodiment of the design;

FIG. 9 is a right side view of the shoe of FIG. 8;

FIG. 10 is a left side view of the shoe of FIG. 8;

FIG. 11 is a front view of the shoe of FIG. 8;

FIG. 12 is a rear view of the shoe of FIG. 8;

FIG. 13 is a top view of the shoe of FIG. 8; and,

FIG. 14 is a bottom view of the shoe of FIG. 8.

The dash-dash broken lines are for the purpose of illustrating portions of the shoe that form no part of the claimed design.

1 Claim, 10 Drawing Sheets(56)
